DESIGN FOR A JAR

Laurence J. Colwell, New York, N. Y., assignor to Charles of the Ritz, Inc., New York, N. Y., a corporation of Delaware

Application October 1, 1940, Serial No. 95,535

Term of patent 14 years

To all whom it may concern:

Be it known that I, Laurence J. Colwell, a citizen of the United States, residing at New York city, in the county of New York and State of New York, have invented a new, original, and ornamental Design for a Jar, of which the following is a specification, reference being had to the accompanying drawing, forming part thereof.

In the drawing:

Fig. 1 is a front elevational view of a jar showing my new design;

Fig. 2 is a top plan view thereof.

Fig. 3 is a bottom plan view.

Fig. 4 is a detail elevational view of the lower part of the wall of the jar between the flower ornaments.

Fig. 5 is a sectional view of the lower part of the wall of the jar, taken on line 5—5 of Fig. 4.

Fig. 6 is a sectional view of a portion of the cover of the jar, taken on line 6—6 of Fig. 1.

I claim:

The ornamental design for a jar, as shown.

LAURENCE J. COLWELL.
